SIGHT FOR FIREARMS

Frederick L. Humeston, New Haven, Conn., assignor to Winchester Repeating Arms Company, New Haven, Conn., a corporation of Maryland

Application February 20, 1934, Serial No. 712,149

5 Claims. (Cl. 33—56)

This invention relates to an improvement in firearm-sights and particularly to adjustable rear sights for firearms, though not so limited.

One of the objects of the present invention is to provide a simple and reliable firearm-sight which may be readily and conveniently adjusted.

A further object is to provide a superior adjustable firearm-sight characterized by simplicity of construction and economy of manufacture.

10 Another object is to provide a simple, reliable and rugged sight which may be adjusted to compensate for so-called "windage," as well as for so-called "elevation."

15 Other objects and advantages will appear to those skilled in the art from the following, considered in conjunction with the accompanying drawing and the appended claims.

In the accompanying drawing:

Fig. 1 is a broken top or plan view of the rear portion of a firearm-barrel, showing a rear sight embodying the present invention mounted thereon;

Fig. 2 is a view thereof in side elevation;

Fig. 3 is a transverse sectional view taken on the line 3—3 of Fig. 2;

Fig. 4 is a transverse sectional view taken on the line 4—4 of Fig. 2;

Fig. 5 is a perspective view of the elevating-screw, detached;

30 Fig. 6 is a similar view of the elevating-screw operating-head;

Fig. 7 is a similar view of the sight-carrier; and

Fig. 8 is a similar view of the sight-base.

The embodiment herein chosen for the illustration of the present invention includes a sight-base generally designated by the numeral 10, preferably formed of spring material, such as properly-tempered sheet-metal, and including a rearwardly-extending flexible arm 11 having its rear end upwardly offset as at 12 and having each of its respective opposite sides adjacent its forward end formed with downwardly-and-inwardly-bent opposed fingers 13—13 embracing a filler-plate 14. The filler-plate 14 just referred to is

40 provided with a central recess 15 into which is pressed as at 16—16 a portion of the respective inner ends of the fingers 13—13, as clearly indicated in Fig. 3. The fingers 13—13 and the filler-plate 14, when assembled together as shown, provide a transversely-extending dovetail-lug 17 for driving fit into a transverse dovetail-groove 18 formed in the upper surface of the firearm-barrel 19 or other suitable member of the firearm.

45 The upwardly-offset portion 12 of the flexible arm 11 of the sight-base 10 is formed adjacent its

rear end with a perforation 20 having its inner end chamfered or countersunk and receiving the rivet-like shank 21 of a tubular pivot or bushing 22. The said bushing 22 is provided with a threaded axial bore 23, an overhanging head 24 and an annular bearing-portion 25, which latter is of lesser diameter than the said head-portion 24 and of greater diameter than the shank 21 before referred to.

5 The forward end of the bearing-portion 25 of the tubular pivot or bushing 22 between the under face of the head 24 and the upper face of the offset-portion 12 of the sight-base 10, is a spring-like sight-carrier 26 preferably formed of suitably-tempered sheet-steel and generally conforming 15 to the shape of the flexible arm 11 of the sight-base. The said sight-carrier is provided with a perforation 27 receiving the bearing-portion 25 of the bushing 22, and includes also an integral upwardly-bent sight-finger 28 having a horizontally-20 arranged internally-threaded sight-aperture 29 which may itself be utilized as a peep-sight, or if desired may receive the externally-threaded shank 30 of an interchangeable peep-sight disk 31 having a usual sight-aperture 32 arranged coaxially 25 of the shank 30 and hence coaxially of the said sight-aperture 29 of the sight-carrier 26.

30 The forward end of the sight-carrier 26 is beveled as at 33 and is suitably indented to provide a downwardly-offset detent-projection or rib 34 adapted to fit in any one of a series of trough-like indented graduations 35 formed in the upper surface of the sight-base 10 and extending beneath the adjacent end of the sight-carrier 26, which latter is suitably tensioned so as to cause 35 the detent-projection 34 to yieldingly engage with any one of the indented graduations 35 to releasably hold the sight-carrier 26 in a selected one of a variety of positions of lateral adjustment.

40 Projecting upwardly into the threaded bore 23 of the tubular pivot 22 is an elevating-screw 36 having a non-cylindrical shank 37 extending into and riveted over in a similarly-shaped perforation 38 (Fig. 6) of an operating-head 39 having 45 its periphery serrated as at 40 or otherwise suitably roughened to provide a convenient finger-grip.

45 The edge portion of the operating-head 39 is downwardly offset as at 41 and is formed in its 50 under face with a plurality of substantially-radial grooves or notch-like recesses 42 into which extends the curved upper surface of the barrel 19 to a degree sufficient to yieldingly restrain the said operating-head 39, and the adjusting-screw 55

of which it forms a part, against accidental turning movement.

When it is desired to change the elevation of the sight-aperture 29 or of the sight-aperture of a peep-sight disk mounted therein, the elevating-screw 36 may be rotated for the purpose referred to by means of the serrated periphery of its operating-head 39, it being understood that the tension of the flexible arm 11 is always exerted 10 downwardly to maintain the under face of the operating-head 39 in engagement with the periphery of the barrel 19 or other appropriate member of the firearm.

In the event that it is desired to compensate 15 for the deflecting effect of wind upon the projectile, the sight-carrier 26 may be swung laterally about the tubular pivot 22, so as to shift its detent-projection 34 into the desired one of the indented graduations 35 as conditions may require, the tension of the sight-carrier 26 itself 20 being such as to yieldingly maintain the said detent-projection 34 in engagement with the selected one of the indented graduations 35.

From the foregoing it will be seen that the adjusting-means is of a simple and rugged character and that the spring-tension of the sight-base itself will serve to engage the under face of the operating-head 39 with the upper surface of the barrel 19 or such other element of the firearm as 30 may be desired, and thus automatically prevent the accidental rotation of the elevating-screw 36 and the consequent unintentional changing of the elevation of the sight.

By employing a tubular pivot or bushing such 35 as 22 and engaging the elevating-screw or equivalent member therewith, not only is superior ruggedness secured, but a marked economy of manufacture is effected.

The invention may be carried out in other specific ways than that herein set forth without departing from the spirit and essential characteristics of the invention, and the present embodiment is, therefore, to be considered in all respects as illustrative and not restrictive, and all changes 45 coming within the meaning and equivalency range of the appended claims are intended to be embraced therein.

I claim:

1. In a firearm, the combination with the bar-

rel thereof having a transversely-curved upper surface; of a sight, including a vertically-yielding member; and a rotary elevating-member for vertically adjusting the said vertically-yielding member, and having a plurality of recesses or 5 grooves in its under face for releasable engagement with the transversely-curved upper surface of the said barrel.

2. A firearm-sight including in combination: a sight-base; a laterally-swinging sight-carrier; 10 a pivot securing the said sight-carrier to the said sight-base with capacity for lateral swinging movement with respect thereto; and a rotary elevating-member mounted for turning movement substantially coaxially with respect to the 15 said pivot.

3. A firearm-sight including in combination: a sight-base; a laterally-swinging sight-carrier; a hollow interiorly-threaded pivot securing the said sight-carrier to the said sight-base with capacity 20 for lateral swinging movement with respect thereto; and a rotary elevating-screw threaded into the said hollow interiorly-threaded pivot.

4. A firearm-sight including in combination: a sight-base; a laterally-swinging sight-carrier; a hollow interiorly-threaded pivot securing the said sight-carrier to the said sight-base with capacity for lateral swinging movement with respect thereto; and a rotary elevating-screw 30 threaded into the said hollow interiorly-threaded pivot, and having an offsetting operating-head provided in its under face with a plurality of recesses or grooves for releasable engagement with an interfiting member of a firearm structure. 35

5. A firearm-sight including in combination: a flexible sight-base having means adjacent one end for attachment to a firearm structure; a laterally-swinging sight-carrier; a pivot securing the said sight-carrier to the said sight-base with capacity for lateral swinging movement with respect thereto; and a rotary elevating-member 40 for vertically flexing the said sight-base and mounted for engagement with and turning movement substantially coaxially with respect to the said pivot.

FREDERICK L. HUMESTON.
